(57) **CLAIM**

The ornamental design for a pallet, as shown and described.

DESCRIPTION

FIG. 1 is a perspective view of a pallet showing my new design;

FIG. 2 is a side plan view of the pallet of FIG. 1, the opposite side being identical to this view;

FIG. 3 is an end plan view of the pallet of FIG. 1, the opposite end being identical to this view;

FIG. 4 is a top plan view of the pallet of FIG. 1;

FIG. 5 is a bottom plan view of the pallet of FIG. 1; and, FIG. 6 is a perspective view of the bottom of the pallet of FIG. 1.
